DEVICE FOR PROCESSING RAW FATS

The present invention relates to devices designed for processing raw fats to be used in food industry.

There is known in the prior art a device for processing raw fats, which is essentially an encased rotatable perforated drum accommodating moveable and stationary knives. The prior art device is equipped with a hopper for charging raw fats and with branch pipes adapted for the delivery of steam inside the casing and for the removal of the mass of obtained fat.

The disadvantage of the known device for processing raw fats lies in that the centrifugal force developed is not sufficient for pressing raw stock into the drum openings and, therefore, does not provide for the transfer of the whole mass of fat. Besides, the fixation of the knives in the housing cover brings about the reduction of the size of a charging hole provided in the cover and impedes the passage of raw stock into the drum. All this causes a decrease in the device's efficiency.

It is an object of the present invention to develop a simple, inexpensive and reliable device that would make it possible to combine in a single machine the technological operations of crushing raw stock, melting fat therefrom and transferring the mass of obtained fat, as well as provide for an increase in the device efficiency.

In accordance with said and other objects, the present invention consists in that in a device for processing raw fats whose drum accommodates at least one stationary and one moveable knife adapted for crushing raw fats, according to the invention, the stationary knives are made L-shaped and have two working blades, the longer of which is designed for cutting large pieces of raw stock and the shorter one forms with the internal surface of the drum an adjustable clearance for trimming on the internal surface of the drum particles of raw stock pressed into the openings thereof in the course of processing, while the inner space of the drum is fashioned as two mating portions, of which one is cylindrical and the other—tapering to provide for an additional feed of raw stock to the stationary knives, the drum cylindrical surface alone being made perforated.

It is expedient that the stationary L-shaped knife be secured in such a manner that the longer working blade be arranged at an acute angle to the internal cylindrical surface of the drum.

For the purpose of adjusting the clearance between the shorter blade and the drum surface the device of the invention can be provided with an arrangement comprising a pin carrying the stationary L-shaped knife secured thereon, a bushing rigidly coupled to the casing and adapted to pass the pin there inside, and a shaped nut to be screwed simultaneously onto said bushing and pin, the pitch of the pin thread being coarser than that of the bushing thread.

It is expedient that the drum be provided with vanes arranged at an angle to the generatrix of the external cylindrical surface of the drum.

The invention will be more apparent upon examining the following detailed description of an exemplary embodiment thereof with due reference to the accompanying drawings, wherein:

FIG. 1 is a general view of the device for processing raw fats, according to the invention;

FIG. 2 illustrates the design of the stationary knife, according to the invention;

FIG. 3 is a view of the stationary knife on arrow A in FIG. 2, according to the invention;

FIG. 4 illustrates the fixation of the stationary knife on the wall of the casing of the device, according to the invention;

FIG. 5 is a view of the drum in section on the axial line, according to the invention;

FIG. 6 shows the device of the invention in section on the line VI-VI of FIG. 1; and

FIG. 7—ditto, section on the line VII-VII of FIG. 1.

The device for processing raw fats comprises a casing 1 (FIG. 1) accommodating there inside a drum 2 rotatable on a shaft 3 of an electric motor 4 mounted on a frame 5. The casing 1 is provided with a hopper 6 for charging raw stock into

the drum 2. The drum 2 is provided with moveable knives 7 rotatable together with the drum and adapted to coarsely crush and uniformly distribute raw fats in the drum. For the purpose of fine crushing of raw stock the drum 2 houses stationary knives 8 (FIGS. 2 and 3).

The stationary knives 8 are made L-shaped and have two working blades 9 and 10.

The longer working blade 9 is disposed in the front portion of the stationary knife 8 and serves, as mentioned hereinbefore, for cutting large pieces of raw stock.

The cutting edge of the longer working blade 9 of the stationary knife 8 is formed by two planes, of which one extends at an acute angle to the generatrix of the internal cylindrical surface of the drum 2 thereby creating an additional force for pressing particles of raw stock into the openings of the drum 2.

The longer working blade 9 of the stationary knife 8 is so tapered that the taper edge in the upper portion of this knife 8 is directed opposite to the direction of rotation of the drum 2, thus making for finer crushing of raw stock.

The other, shorter, working blade 10 of the stationary knife 8 is in the rear portion of the knife and forms an adjustable clearance with the internal surface of the drum 2. This latter blade is designed for trimming particles of raw stock pressed into the openings of the drum 2.

For the purpose of adjusting said clearance between the shorter working blade 10 of the stationary knife 8 and the internal surface of the drum 2, the device according to the invention is provided with an arrangement comprising a pin 11 (FIG. 4) with the stationary knife 8 rigidly secured thereon, a bushing 12 and a shaped nut 13.

The bushing 12 adapted to pass the pin 11 there inside is rigidly coupled to the casing 1 on the external surface of the latter.

The pin 11 is prevented from rotating about its axis by the provision of a sliding dowel or a flat (the dowel and flat not shown in FIG. 4).

The shaped nut 13 has two internal threads 13a and 13b with different pitch, to simultaneously screw said nut 13 onto the bushing 12 and the pin 11.

The pitch of the thread 13b serving to screw the nut 13 onto the pin 11 is coarser than that of the thread 13a serving to screw the nut 13 onto the bushing 12, owing to which one full revolution of the nut 13 (when it is being simultaneously screwed onto the pin 11 and the bushing 12) brings the pin 11 closer to the internal surface of the drum 2 by a value equal to the difference in pitch of the threads 13a and 13b.

For locking the stationary knife 8, the pin 11 is provided with a pawl 14 adapted to enter one of the slots in the shaped nut 13 after the latter is screwed on.

The device according to the invention is provided with the above-listed arrangements in an amount corresponding to the number of the stationary knives 8, of which there can be several. Shown in FIGS. 6 and 7 are two stationary knives 8.

The drum 2 (FIG. 5) is made as two mating portions, a cylindrical portion 15 and a tapering portion 16 converging towards the bottom 17.

The cylindrical portion 15 of the drum 2 is made perforated, while the tapering portion 16 is designed for changing the direction of movement of raw stock on the bottom 17 of the drum 2 towards the stationary knives 8 to create an additional force when raw stock moves under the cutting edge of the longer blade 9 of the knives 8.

The drum 2 is provided on the external surface with vanes 18 (FIG. 4) serving to discharge the mass of obtained fat from the space formed between the casing 1 and the drum 2 and to create pressure head.

The vanes 18 are installed in the direction of rotation of the drum 2 at an angle to the generatrix of the cylindrical portion 15 of the drum surface.

This angle of setting the vanes 18 on the drum can be from 0° to 50° and is formed between the vanes 18 and a tangent passing at the point of fixing a vane 18 to the cylindrical portion of the drum surface.

Preferably, this angle should be set from 10° to 20°.

The drum 2 can have several vanes 18 (shown in FIG. 6 are only two vanes 18).

For the delivery of the heat-carrying agent, for example steam, into the space formed between the casing 1 and the rotatable drum 2 provision is made of an inlet branch pipe 19 (FIGS. 6 and 7), while the fully processed (following the crushing and melting operations) mass of fat is removed from said space via an outlet branch pipe 20.

The casing 1 can be provided with several inlet branch pipes 19 for the delivery of the heat-carrying agent, secured to the casing at any angle to the generatrix thereof. Shown in FIGS. 6 and 7 is the connection of one inlet branch pipe 19 to the casing 1 in the middle portion thereof.

The outlet branch pipes 20 are connected to the casing 1 tangentially to the cylindrical surface thereof; there can be several such outlet branch pipes in the device according to the invention. Shown in FIGS. 6 and 7 is the connection of one outlet branch pipe 20 to the casing 1.

For more convenient servicing the device according to the invention can be arranged at an angle to the vertical axis, as shown in FIG. 1.

The device of the present invention operates in the following manner.

Raw fats from the hopper 6 (FIG. 1) pass into the rotating drum 2 to be precrushed by the moveable knives 7. Thereupon, raw stock is centrifuged to the internal wall of the drum 2 where it is crushed by the longer blades of the stationary knife 8 into smaller pieces.

Under the action of centrifugal force the coarsely precrushed stock fits tightly against the cylindrical surface 15 of the drum 2 and is pressed into the openings.

Particles of raw stock pressed into the openings of the drum 2 are trimmed by the shorter blades 10 of the stationary knife 8. The clearance between the blade 10 and the drum 2 can be adjusted with the machine running.

Crushed raw stock passes further into the space between the casing 1 and the drum 2 wherein the heat-carrying agent (steam) delivered via the branch pipe 19 (FIGS. 6 and 7) heats the particles of raw stock in suspended state and melts fat therefrom. The mass of obtained fat is discharged with the aid of the vanes 18 via the branch pipe 20.

When using the device of the invention in production lines for fat melting, the operations of coarse and fine crushing of raw stock, melting fat therefrom and transferring the mass of obtained fat are combined in a single machine, at a reduced number of such machines and lower metal consumption of the

lines.

Besides, the device according to the invention possesses a number of advantages, mainly:

high efficiency;
simple design, convenient control and easy access for sanitary purposes;

small overall dimensions;
high factor of heating steam utilization owing to the direct contact of steam with raw stock;

short time of heat action upon raw stock, which improves the quality of fat.

Although the present invention has been described in connection with a preferred embodiment thereof, various alterations and modifications can be made without departing from the spirit and scope of the invention, as those skilled in the art will easily understand.

Such alterations and modifications are to be considered as falling within the essence and scope of the invention and the appended claims.

20 We claim:

1. A device for processing raw fats, comprising: a casing; a drum adapted for crushing raw stock, whose inner space is made as two mating portions, of which one is cylindrical and perforated and the other tapering; moveable knives; stationary knives made L-shaped and having two working blades each—a longer one and a shorter one; said longer blade being designed for cutting large pieces of raw stock, while said shorter blade forms with the internal surface of the drum an adjustable clearance for trimming on the internal surface of the drum particles of raw stock pressed into the openings thereof in the course of processing.

2. A device as set forth in claim 1, comprising said stationary L-shaped knife secured in such a manner that the longer working blade is arranged at an acute angle to the internal cylindrical surface of the drum.

3. A device as set forth in claim 1, comprising an arrangement adapted for adjusting the clearance between said shorter blade and the surface of said drum, including; a pin carrying said stationary knife secured thereon; a bushing rigidly coupled to said casing and adapted to pass said pin there inside; a shaped nut to be screwed simultaneously onto said bushing and said pin, the pitch of the pin thread being coarser than that of the bushing thread.

4. A device as set forth in claim 1, comprising said drum provided with vanes arranged at an angle to the generatrix of the cylindrical surface of said drum.
